(57) **CLAIM**

The ornamental design for a vehicle front grille as shown and described.

DESCRIPTION

FIG. 1 is a right upper perspective view of a vehicle front grille, showing my new design;

FIG. 2 is a right side elevational view thereof, the left side being a mirror image;

FIG. 3 is a front elevational view thereof;

FIG. 4 is a rear elevational view thereof;

FIG. 5 is a top plan view thereof; and,

FIG. 6 is a bottom plan view thereof.

The dash-dash broken lines illustrate portions of the vehicle front grille that form no part of the claimed design. The areas within the perimeter of the broken lines form no part of the claimed design.
